UNITED STATES PATENT OFFICE.

JOHN PIEPERGERDES, OF STEWARTSVILLE, MISSOURI.

GATE.

No. 872,844.

Specification of Letters Patent.

Patented Dec. 3, 1907.

Application filed May 27, 1907. Serial No. 375,924.

To all whom it may concern:

Be it known that I, JOHN PIEPERGERDES, a citizen of the United States, residing at Stewartsville, in the county of Dekab and 5 State of Missouri, have invented certain new and useful Improvements in Gates; and I do declare the following to be a full, clear, and exact description of the invention, such as will enable others skilled in the art to which 10 it appertains to make and use the same.

This invention relates to improvements in gates.

The object of the invention is to provide a gate adapted to be opened and closed by a 15 person approaching either side without the necessity of alighting from a horse or vehicle.

A further object is to provide a gate of this character which will be simple, strong, and durable in construction, efficient and reliable 20 in operation, and having means whereby the operating parts of the same are protected from the weather.

With these objects in view, the invention 25 consists of certain novel features of construction, combination and arrangement of parts as will be more fully described and particularly pointed out in the claims appended.

In the accompanying drawings, Figure 1 is 30 a side view of one side of the gate, showing the same in closed position; Fig. 2 is a similar view, showing the gate open; Fig. 3 is a side view of the opposite side of the gate, showing the latter in closed position; and Fig. 4 is a vertical sectional view on the line 4—4 of 35 Fig. 1.

Referring more particularly to the drawings, 1 denotes the main supporting post, which is arranged at one side of the road. On the opposite side of the road, in line with 40 the post 1, is arranged a post 2, against which the gate is held when in closed position. On the opposite side of the main post 1 at a suitable distance therefrom is arranged a post 3, with which the gate is engaged when in 45 open position. Pivotaly mounted on one side of the main post, 1, adjacent to its upper end, is a track supporting and protecting bar, 4, said bar being inclined upward from its outer end toward its center, as shown. 50 The outer end of the bar 4 adjacent to the post 2 is provided with a hook 5 which is adapted to be engaged with an eye or keeper, 6, on the upper end of the post 2, whereby said track supporting bar 4 is normally held

in a closed or operative position. Secured to 55 the lower side of the bar, 4, at its opposite ends, is a gate supporting track 7, said track being inclined from its outer ends toward the center and substantially parallel to the bar 4 and spaced therefrom to a suitable distance. 60 The central portion of the track bar 7 is supported and braced by a depending hanger 8, which is secured to the underside of the bar 4.

Connected at its opposite ends to the post 1 and the post 3 is a track supporting and 65 protecting bar 9, said bar 9 being inclined upward from its opposite ends toward the center, as shown. Secured to the underside of the bar 9 and spaced at a suitable distance therefrom, is a second gate supporting track 70 10, said track being inclined from its ends toward the center, where it is supported and braced by a hanger, 12.

Slidably supported on the tracks 7 and 10, is a gate 13, said gate being here shown as 75 provided with an upwardly projecting outer post, 14, on the upper end of which is secured a bearing bracket 15, in which is journaled a supporting pulley, 16, adapted to engage and travel on track 7. The opposite end of the 80 gate 13 is provided with a post 17, on the upper end of which is arranged a bracket 18, in which is journaled a gate supporting pulley 19, adapted to engage and travel on the track 10 to support the inner end of the gate 85 in an open or closed position.

Arranged along the side of the road at a suitable distance from the main post 1 and on opposite sides of the same are pivot posts, 20, on which, adjacent to their upper ends, 90 are pivotally mounted operating levers, 21 and 22, the inner ends of which are disposed one above the other, and are pivotally connected together by plates, 23. The inner ends of the levers 21 and 22 are connected at 95 one side of the post, 1, over the bar 9; and the lever 22, which passes the post 1, is held in position by a guide bar, 24, arranged on the post 1. Loosely connected to the underside of the inner end of the lever 22 is the upper end of an operating rod 25, the lower end of which is pivotally connected with the lower end of an operating bar, 26, which is pivoted to the center of the adjacent side of the gate, as shown. The upper end of the operating bar 26 projects above the gate and is bent at right angles thereto, and connected to a stop chain, 27, the opposite end of which

is connected to the post 1, as shown. When the gate 13 is in a closed position, the bar 26 is disposed at an angle with its upper end projecting toward the post 1, so that when the 5 operating levers 21 and 22, are pulled down on either side of the gate, the inner ends of said levers will be raised and the operating rod connected thereto will draw upon the operating bar 26, which, owing to its position, will lift 10 the gate and pull the same laterally until the pulleys on the upper ends of the post of the gate are brought past the inclined central portion of the tracks, after which the weight of the gate will cause the pulleys to travel 15 down the opposite inclined portion of the tracks and carry the gate to an open position at one side of the road, as shown in Fig. 2 of the drawings. As the gate is thus swung to an open position, the operating rod 25 will 20 swing the lower end of the bar 26 in the opposite direction, thereby reversing the position of said bar, so that when the operating lever on the other side of the gate is pulled down, the gate will be raised and drawn back 25 to a closed position in the same manner in which it is opened.

On the side of the gate adjacent to the supporting post is arranged a longitudinally disposed bar or track, 28, which is adapted to 30 engage an elongated vertically disposed roller, 29, which is journaled in a suitable bracket on the side of the post 1, and provides a bearing with which the gate is engaged when being moved to its open or 35 closed position, thus preventing the gate from binding against the post 1. Arranged oppositely to the post 1 and the post 2, are short guide posts, 30 and 31, the post 30 serving to hold the gate and guide the same 40 in its opening and closing movement, while the post 31 serves to hold the gate in closed position against the post 2. The post 2 is provided adjacent to its upper end with an inwardly projecting stop having a beveled 45 inner end adapted to be engaged by the gate when brought to a closed position to guide the same into engagement with the side of the post, and also to provide means for preventing the gate from being pushed inwardly 50 should the same not be entirely closed against the post 2.

By hingedly mounting the inner end of the track supporting and protecting bar 4 on the post 1, said bar may be swung upwardly to 55 permit the passage of high vehicles through the gate, the bar 4 being secured in its lowered or normal position by means of the hook 5, which engages the keeper 6 on the post 2. When the bar 4 is raised the track 7 will also 60 be moved up therewith. This upward movement of the track 7 will elevate the forward end of the gate to a slight extent, owing to the engagement therewith of the pulley 16 on the upper end of the outer gate 65 post, 14.

The guide bar 24 on the post 1 which holds the lever 22 in place, is bent inwardly at its upper portion to form a shoulder 24^a with which the lever 22 will be engaged and held against operation should an attempt be made 70 to open the gate in any other manner than by the means of the levers, thereby preventing the opening of the gate by stock. Should any attempt be made to push the gate open, the operating bar 26 will cause the operating 75 rod 25 to force the lever 22 back, thus causing the same to engage the shoulder 24^a in the guide bar 24 which will prevent said lever from rising and thereby hold the gate in closed position. 80

Having thus fully described my invention, what I claim as new and desire to secure by Letters-Patent, is:

1. In a gate of the character described, the combination with a main and side supporting post, gate supporting tracks arranged on and secured to said supporting posts and extending on opposite sides of the main supporting posts, a gate having upwardly projecting end posts, supporting pulleys journaled on the upper ends of said posts and adapted to be engaged with said supporting track, lever posts arranged along one side of the road and opposite sides of said main supporting posts, operating levers pivoted on said lever posts, means to loosely connect the inner ends of said levers together, an operating bar pivotally mounted on said gate, an operating rod to connect the lower end of said bar with the inner ends of said levers, a stop chain to 100 connect the upper end of said bar with said main supporting post, means to guide said gate in its open and closing movements, and means to prevent the same from binding against said track supporting posts, substantially as described. 105

2. In a gate of the character described, the combination with a main and side supporting posts, of gate supporting tracks arranged on said posts and extending in each direction on opposite sides of said main supporting post, said tracks being inclined from their outer ends toward their center, means to protect and cover said tracks, a gate having upwardly projecting end posts, bearing brackets on the upper ends of said posts, supporting pulleys journaled in said brackets and adapted to be engaged with said brackets, pivotally mounted operating levers extending along the side of the road at suitable distances on each side of said main supporting post, an operating mechanism connected with said levers and with the gate, whereby the latter is raised and drawn toward the center of said tracks until the supporting pulleys 120 thereon pass the inclined center of the tracks, whereby the weight of the gate will cause the same to continue to open or close, guide posts arranged opposite said main supporting post and the closing post of the gate to 130

guide and hold said gate in position, a bearing track on one side of said gate, a bearing roller journaled on said main supporting post and adapted to be engaged by said track, and an inclined guiding and gate holding block arranged on the closing posts of the gate, substantially as described.

In testimony whereof I have hereunto set my hand in presence of two subscribing witnesses.

JOHN PIEPERGERDES.
